METHOD OF AROMATIZING
HYDROCARBONS

Robert F. Ruthruff, Nutley, N. J., assignor to The
M. W. Kellogg Company, New York, N. Y., a
corporation of Delaware

Application April 23, 1938, Serial No. 203,886

3 Claims. (Cl. 260—668)

My invention relates to a method of aromatizing hydrocarbons.

It is well known that for many applications petroleum naphthas and other light petroleum hydrocarbons of high aromatic content are desirable and necessary; in fact only under the most unusual circumstances does the presence of aromatics in petroleum naphthas limit their application. A high aromatic content is desirable in high solvency naphthas employed in the lacquer industry and the presence of compounds such as toluene and xylene is very beneficial in aviation fuels. It has heretofore been recognized that aromatic hydrocarbons can be obtained by the thermal decomposition of hydrocarbons, the aromatic content of the reaction product increasing normally with increased severity (i. e., increasing temperature) of treatment. During the pyrolytic treatment of hydrocarbons to produce aromatics unsaturated hydrocarbons are invariably obtained as a by-product. In many applications the presence of olefins in the aromatic-rich naphtha is undesirable or in many cases prohibited. For example, aviation fuels should contain only a minor amount of olefins, while in the case of high solvency naphthas the presence of olefins is altogether undesirable. Furthermore if the aromatics are to be used in chemical synthesis (e. g., sulphonation, nitration, or the like) olefins must be absent for obvious reasons.

Heretofore it has been suggested by investigators conducting research along these lines that olefins be removed from the aromatic-rich mixtures formed, for example, by the high temperature pyrolysis of hydrocarbons, by hydrogenation. This procedure will remove olefins but it is very unsatisfactory since unless the reaction is controlled with great accuracy aromatics will also be hydrogenated. In addition, I have found that hydrogenation in such cases is not only unsatisfactory but is in fact the antithesis of the proper procedure, dehydrogenation rather than hydrogenation being preferred.

Evidently the advantages of dehydrogenation have either been overlooked or not been realized by previous investigators, probably because they were unaware of the fact that the unsaturated hydrocarbons present in aromatic-olefin mixtures formed by high temperature pyrolysis of hydrocarbons are not olefins in the usual sense but consist substantially of cyclo-olefins. Upon hydrogenation these cyclo-olefins are converted to naphthenes but in the instant process these are further dehydrogenated to form aromatics and any residual olefins thereafter removed by a

mild hydrogenation or by other means. My invention may perhaps be best understood by illustrative examples.

For instance, a gas reversion naphtha having approximately the following composition, was treated in the process:

	Per cent
Olefins	35
Aromatics	25
10 Naphthenes	15
Paraffins	25

This material was produced by cracking naphtha under high temperature and pressure in the presence of the readily condensable gas formed in the reaction. The charge after passing through the cracking or reaction zone was separated by fractionation into cuts representing:

1. Methane, hydrogen and most of the C₂ hydrocarbons
- 20 2. C₃ and C₄ hydrocarbons
3. Gas reversion gasoline
4. Polymer

The second cut was recycled and added to the naphtha charge. Obviously, condensables from an extraneous source may be used to increase the amount of cut #2 if desired.

By catalytically hydrogenating the above material under as mild conditions as possible consistent with complete olefin removal, the resulting product would have approximately the following composition:

	Per cent
Aromatics	15
35 Naphthenes	65
Paraffins	20

From the above it is evident that by hydrogenation methods all of the olefins and a large part of the aromatics have been hydrogenated to naphthenes.

Contrasting this procedure with results obtained by the employment of my suggested method, namely, the dehydrogenation of the gas reversion gasoline such as the material indicated above, a product having approximately the composition tabulated below is obtained:

	Per cent
Aromatics	70
50 Olefins	10
Naphthenes	5
Paraffins	15

Subsequent to the above dehydrogenation there may be optionally used a second step of mild hydrogenation in which the residual olefins

are removed and a final product obtained having the composition given below:

	Per cent
Aromatics	60
Naphthenes	20
Paraffins	20

In the dehydrogenation step I preferably employed a dehydrogenating ring closing catalyst such as a chromium oxide deposited upon alumina as a carrier in the proportions of 10% chromium oxide to 90% alumina. As an alternative method of operation a straight dehydrogenating catalyst may be used such as metallic nickel deposited on pumice.

A second application of the process is the treatment of highly aromatic liquids produced by high temperature pyrolysis of gaseous or liquid hydrocarbons at sub-atmospheric to moderately high super-atmospheric pressures in the manufacture of commercial gas. It is conventional practice in the manufacture of gas to burn a fuel gas with theoretical air (controlled to produce a substantially neutral atmosphere during burning), and into the combustion gases atomize a Mid-Continent gas oil. The aromatic liquids are obtained in this procedure by fractionation and removal of relatively heavy bottoms and the recovery of the aromatics to be treated by separation of fractions taken overhead. A liquid containing up to 70% aromatics or more is obtained in this manner. These fractions are in some cases adapted to use as solvents in the paint industry or for other purposes. From the vapors formed by taking 70% overhead and maintaining a top tower temperature of approximately 540° F. a liquid may be fractionated which is highly aromatic. Such a liquid is advantageously treated for its improvement and elimination of objectionable characteristics. Tests made upon a distillate produced in this way, the inspections on which are shown in the first column of Table I, those on a cut representing a 70% overhead fraction from this material being given in the second column, will now be considered.

TABLE I

	Column No.			
	1	2	3	4
Stock	Total Dist. 26.3	70% OH 34.1	Hyd. 70% OH 35.7	Dehyd. 70% OH 34.8

Residue	Coke	1.1	1.2	1.1
Loss		0.4	0.3	1.4
Percent Olefins		90.3	67.4	(1)
Percent acid absorption		77.0	67.0	(1)
Aniline point, °F.	32	50	(1)	

¹ See Table II.

To make comparative tests on the distillate a 70% overhead cut was produced by distillation. In column 3 there are indicated the gravity, distillation range, and other characteristics of a product resulting from the hydrogenation of the material shown in column 2. In column 4 there

are indicated the gravity, range of boiling point and other characteristics obtained from the dehydrogenation of the material shown in column 2.

Upon the accompanying drawing which forms a part of the instant specification and which is to be read in conjunction therewith, there is plotted percentage overhead against top tower temperature in degrees centigrade, the curve identified by the letter "A" indicating the olefin content, curve "B," the specific gravity, and curve "C," the top tower temperature.

The specific gravity of overhead cuts, each representing 1% of the charge, was determined at 20° centigrade. The curve exhibits a number of maxima and minima, behavior characteristics of cuts obtained by fractionating mixtures containing hydrocarbons of various types. The olefin content of each 0.5% cut was determined by measuring the bromine absorption. It is significant to note that in the lower temperature region olefin content varies inversely with specific gravity, that is, maxima in olefin content corresponding to minima in the specific gravity curve and vice versa.

By the simultaneous consideration of tower top temperature, specific gravity and olefin content it is possible to obtain an approximation of the types of hydrocarbons present in a given cut. All three curves, "A," "B," and "C," are plotted upon a single chart to facilitate simultaneous comparison, each curve showing the variation of but one property at the particular percent off.

It will be noted that at the start of the distillation (i. e., up to 4% overhead), temperatures and specific gravity mount rapidly, while olefin content declines. It is believed that this represents a gradual change in the overhead cuts from highly olefinic to highly aromatic content. The first minimum in the specific gravity curve is probably attributable to a cut rich in benzene. Between the first and second peaks in specific gravity there is a second maximum in the olefin content curve (7% off). This again is due to a highly unsaturated fraction, but the specific gravity, although at a minimum is still high (0.77), showing that the olefins present belong to the cyclic series. In this range, all olefins of the usual type (e. g., the heptenes) have specific gravities of only 0.69 to 0.72, but cyclic olefins have specific gravities in the neighborhood of 0.80. It is evident that the highly olefinic cut at approximately 7% off consists largely of cyclo-olefins. The second specific gravity peak (10% off) is attributed to a toluene-rich product. Immediately beyond this is a third olefin peak, practically coincident with a minimum but high specific gravity (0.80). Olefins (in the usual sense) of this boiling range have gravities of 0.70 to 0.73, so here again the olefins present must be largely of a cyclic nature.

The same reasoning can be applied throughout the distillation range but obviously the analysis becomes increasingly complex as the percentage overhead increases. It is, however, a warranted conclusion that this distillate consists largely of cyclic compounds (aromatics, cyclo-olefins, cyclo-diolefins, and naphthenes). On this basis hydrogenation to remove components of olefins is theoretically improper and the antithesis of the proper procedure for the following reasons. When a mixture consists substantially of cyclo-olefins, naphthenes and aromatics, and is hydrogenated, the cyclo-olefins are converted to naphthenes, the naphthenes remain

unchanged, while the aromatics are also changed to naphthenes. It is obvious that if a highly aromatic final product is desired hydrogenation is not the preferred procedure; while the hydrogenation conditions may be so regulated that little or no aromatics are destroyed yet it is obvious that aromatics cannot be increased by this procedure.

On the other hand, if the above mixture is dehydrogenated, the cyclo-olefins and naphthenes are readily converted to aromatics, while the aromatics themselves remain unchanged. By this latter procedure the quality of the distillate is improved, while by hydrogenation at best it remains constant. Results obtained from the effect of hydrogenation on a 70% overhead cut topped from this distillate, characteristics of which are shown in column 1, are found in column 3 of the table. The 70% overhead cut shown in column 2 contains 90% of olefins by bromine absorption, but only 77% of olefins and aromatics by acid absorption, indicating that an appreciable part of the olefins present are di-olefins, and from the previous statements these must be largely cyclo-diolefins.

The 70% overhead material or product of column 2 was catalytically hydrogenated at 200# and 485° F. with a resultant product as shown in column 3 of the tabulation. Inspection will show that the olefin content has been reduced considerably by hydrogenation, while the aniline point is increased, indicating that the suitability of the material for high solvency naphtha has been lowered. By adjustment of conditions it might be possible to hydrogenate the stock without destroying appreciable aromatics.

The same material, namely, that of column 2 of the tabulation, was catalytically dehydrogenated at 932° F. and atmospheric pressure in two runs of five hours' duration. While this specific temperature is given (932° F.), the invention contemplates as well a range of temperature of from 850° F. to 1200° F., a normal operating range being between 900 to 1000° F. The products of each run were collected in two parts, representing 2.5 hours on stream, and 2.5-5 hours. An inspection and comparison of the four samples can be made from the following tabulation:

TABLE II

Dehydrogenation of 70% overhead

Charge	First run		Second run	
	0-2.5 hrs.	2.5-5 hrs.	0-2.5 hrs.	2.5-5 hrs.
Gravity, °A. P. I.	34.1	36.5	35.6	35.6
Percent olefins	90.3	66.4	78.5	76.0
Percent acid absorption	77.0	77.0	77.0	77.0
Aniline point, °F.	32	23.5	25.5	19.0
				24.5

It will be noted from the above tabulation that on dehydrogenating this stock the olefin content of the product declines, indicating that dehydrogenation produces an improvement not effected by hydrogenation. Also, while the olefin content of the charge is higher than the acid absorption, indicating the presence of appreciable diolefins, the olefin content of the dehydrogenated product is equal to or less than the acid absorption, showing that considerable diolefins have been destroyed. The dehydrogenation step also improves the aniline point. It will be noted that olefin content and aniline point

of the samples obtained over the period of 2.5-5 hours are higher than those recovered during the first 2.5 hours. This is due to the gradual decline in catalytic activity as the operation proceeds.

When the catalyst has been exhausted to the extent that it is deemed necessary to revivify it, revivification will revert it substantially to its original activity. The period of operation before revivification will depend upon the rapidity of catalyst poisoning. For comparison of the results obtained on hydrogenation and dehydrogenation the same catalyst was used.

A subsequent hydrogenation step in the presence of a catalyst may be added as a step to supplement the dehydrogenating step and further convert or remove any residual olefins. This additional step of hydrogenation is optional as indicated in the first example explained.

From the foregoing, it will be apparent that the instant invention lies in the discovery that a mixture of hydrocarbons containing aromatics and cyclo-olefins may be subjected to dehydrogenation by any appropriate method to accomplish two results, namely,

- (a) destroy the cyclo-olefins,
- (b) form aromatics.

The instant invention does not lie in a new method of dehydrogenation per se, but in the discovery that dehydrogenation may be applied to a particular type of hydrocarbon to accomplish unobvious and useful results. Previous investigators have tried to obtain an aromatic containing mixture free from olefins by hydrogenating the olefins. It will be clear from the foregoing that this is an ineffective and undesirable method. If, after the dehydrogenation, the residual olefin content is still too high, a mild hydrogenation may be practiced upon the resultant product to remove residual olefins, if desired.

It will be understood that certain features and sub-combinations are of utility and may be employed without reference to other features and sub-combinations. This is contemplated by and within the scope of the claims. It is obvious that various changes may be made in the operating conditions within the scope of the claims without departing from the spirit of the invention. It is therefore understood that the invention is not limited to the specific details shown and described.

Having thus described my invention, what I claim is:

1. A method of producing hydrocarbons relatively free of olefins and having a high aromatic content which comprises cracking high boiling hydrocarbons in the presence of added normally gaseous hydrocarbons, thereby producing a naphtha fraction rich in aromatics and containing olefinic constituents largely in the form of cyclo-olefins of six or more carbon atoms, contacting said fraction with a dehydrogenation catalyst at a temperature between 850° to 1200° F. at substantially atmospheric pressures thereby decreasing the olefinic content and increasing the aromatic content of the fraction, and catalytically hydrogenerating the dehydrogenated product under as mild conditions as possible consistent with substantially complete hydrogenation of residual olefins.

2. A method of producing hydrocarbons relatively free of olefins and having a high aromatic content which comprises cracking gas oil to produce a fraction relatively rich in aromatics and cyclo-olefins of six or more carbon atoms by atomizing the gas oil into hot combustion prod-

ucts of normally gaseous hydrocarbons, separating the fraction rich in aromatics from the relatively heavy bottom fraction, contacting the separated fraction with a dehydrogenation catalyst at a temperature between 850° to 1200° F. at substantially atmospheric pressures thereby decreasing the olefinic and increasing the aromatic content of the fraction, and catalytically hydrogenating the dehydrogenated product under as mild conditions as possible consistent with substantially complete hydrogenation of residual olefins.

3. A method of producing hydrocarbons relatively free of olefins and having a high aromatic content, which comprises cracking naphtha in the presence of recycled C₃ and C₄ hydrocarbons

formed during the cracking reaction thereby producing a hydrocarbon fraction rich in aromatics and containing olefins largely in the form of cyclo-olefins of six or more carbon atoms, contacting said fraction rich in aromatics with a dehydrogenation catalyst at a temperature between 850° to 1200° F. at substantially atmospheric pressures thereby decreasing the olefinic and increasing the aromatic content of the fraction, and catalytically hydrogenating the dehydrogenated product under as mild conditions as possible consistent with substantially complete hydrogenation of residual olefins.

ROBERT F. RUTHRUFF.
